UNITED STATES PATENT OFFICE.

EMIL A. BRINER, OF EAST ORANGE, NEW JERSEY.

METHOD OF HEATING AND VENTILATING AND APPARATUS THEREFOR.

Application filed May 27, 1919. Serial No. 300,197.

To all whom it may concern:

Be it known that I, EMIL A. BRINER, a citizen of the United States, residing in East Orange, county of Essex, and State of New Jersey, have invented certain new and useful Improvements in Methods of Heating and Ventilating and Apparatus Therefor, of which the following is a full, clear, and exact description.

This invention relates to the art of building ventilation and auxiliary drying processes, and has particular reference to the recovery of heat from the waste hot air, vapors, and gases resulting from the drying of paper, textiles, food products, or from cooking or evaporating, the improvement of conditions in the building in which such drying operations are carried on, and to a means for accomplishing these results.

While I will describe the method and improvements especially as applied for use with paper machinery, it is to be considered as merely illustrative, for the invention in its broader aspect is capable of general application to building ventilation in heating the necessary air supply, and wherever used with drying processes from which vapor laden gases arise.

Heretofore in nearly all processes of drying, the resultant hot moist air, gases, or vapors have been allowed to escape in a wasteful manner. The temperature has been raised to a high degree in order to permit the absorption of more vapor. The hot mixture has heat energy in the form of the sensible heat of the air and vapor and the latent heat of the vapor. In many processes the latent heat energy is greater than the sensible heat energy. Not only is this loss of heat energy an economic one which is considerable in some processes, but there is also an indirect loss to the plant on account of impaired working conditions generally heretofore unavoidable in rooms wherein drying processes were carried on.

The distinguishing feature about my method of utilizing heat of the waste vapor is that I use it primarily for heating outdoor air as a fresh air supply for building ventilation external to the drying process or drying chamber. In order for this method to be successful, I have to actually condense the vapor because the temperature of the

waste hot air, in itself, is generally too low to be of any commercial value. It is usually between 100 and 120 degrees Fahrenheit in paper drying processes. It is necessary to go beyond the mere superficial method of sensible heat interchange so as to utilize the latent heat of condensation of a vapor dissolved in air.

My method is adaptable for utilizing waste heat recovered from a drying or evaporating operation in order to heat and ventilate an adjoining building. Such use is distinctly feasible and practical as the primary purpose of the invention is heating and ventilating, both adjoining buildings, and the building in which paper drying is carried on.

However, by using the method described for recovering waste heat for ventilation of the building space surrounding the drying operation, it enables one to obtain still greater economy by a further use of ventilating air for secondary use as an absorbent of steam vapor.

Both the heating and ventilating function (called primary use) and the absorbing function (called secondary use) of the air have been found to be necessary features for proper atmospheric air conditions of buildings used for paper drying and both functions are of substantially equal importance. I have used the expressions primary and secondary as indicating more clearly the preferred order of operation in my method of securing exceptional economy. It is also feasible to reverse this order of operation.

It is evident that this primary and secondary use of air represents a single continuous cycle of use for the fresh air supply. A distinctive feature of my method in actual practice is its successful operation independent of either a tight building or an enclosed dryer unit. In paper mills the drying rolls are almost universally open type machines enabling the machine tender to watch the sheet and handle breaks that occur on the drying rolls. The machine building itself usually has open doors at either end for communication into beater building and shipping buildings. Such openings usually help to provide cooler air to the lowest air stratum at the floor, independent of my system or process. In other

words my system or process is universal in its application and does not depend for operation upon an enclosed dryer, or upon close connections with such dryer unit either 5 for vent air, fresh air, or both.

As is well known, the present method for drying of paper web on a paper machine is effected by passing the web over a series of hot rolls which are heated internally by 10 steam. This results in the formation of a large volume of water vapor which is absorbed by warm air near the machine and allowed to escape through openings in the roof, either by natural draft or by suction 15 draft caused by any air moving device drawing the hot air and vapor through a hood placed immediately over the machine and discharging the moisture laden air outdoors. A machine producing 100 tons of news- 20 print paper every twenty-four hours requires the evaporation of 200 tons of water per day. An average of 100,000 cubic feet of air per minute is necessary to carry away these vapors. The energy in so much heated air and warm vapor is greater and, in the 25 practice of the herein-described process, the equivalent to about 200 boiler horse power may be recovered.

The usual practice in the drying of paper 30 in paper mills is to allow the vapor to be carried toward the roof by warm air near the machine. The roof being at a lower temperature than the vapors causes a condensation of part of the vapors on the under side of roof and results in what is known as "drip." To prevent this condensation, hoods are often used and steam coils are placed under the roof to keep the air warm, or hot dry air is directed against the under 35 side to warm the roof. But in so doing, these methods augmented by the drying process raise the temperature of the whole room to a point where conditions are not satisfactory for comfort of the machine 40 tenders.

In nearly all processes of drying, the resultant hot air or gases or vapors are allowed to escape as waste. The purpose of this invention is to recover part of the heat 50 of the hot air or gases or vapors and use it to heat fresh air primarily for heating and ventilating purposes, and secondarily as an absorbent of vapor from a drying or evaporating process. The efficiency of the drying 55 process is the ratio of amount of heat utilized to the total amount of heat supplied.

I increase this efficiency by increasing the amount of heat utilized in any given dryer or provide fresh warm air for various other 60 purposes.

My invention is primarily a heating and ventilating process taking moist air out of a building and rapidly replacing it with fresh air. The advantage of such process 65 over other processes lies in the fact that such

fresh outdoor air is always suitable for heating and ventilation of a building, while its direct use in an enclosed dryer is not satisfactory because such extremely dry air dries the outside surface of materials, which 70 in nearly all cases are subsequently checked or cracked by the expansion into steam of moisture held in the center of the material by the relatively impervious surface.

My ventilating process may be supplemental to a drying process, especially where the drying operation is of a continuous character like in paper mills, in contradistinction to ordinary batch driers which are intermittent in operation and do not give off a continuous supply of vapor.

It is therefore an object of my invention to so process these vapors that their heat energy may be largely retained in the system, so that the economic loss is minimized. 85 Such a process includes a subjection of the waste gases or vapors to an economizer where they are cooled to such an extent that the air cannot retain more than a small portion of the vapor with which it was first charged. The vapor is condensed in the economizer and forced to give up its latent heat energy, thereby raising the temperature of the economizing medium, generally 90 fresh air. This warm fresh air has a much lower relative humidity than it had originally and is available in large quantities for heating, or for providing warm fresh air to absorb the vapors necessary for continuing 95 the process. The condensate is returned as 100 warm liquid ready to be used as such.

Another object of my invention is to remove the vapors from the room rapidly so that working conditions may be improved.

Another object of my invention is to improve conditions directly under the roof so that the objectionable drip is avoided without the use of auxiliary heaters.

Another object of my invention is to provide an economizer or vapor condenser suitably arranged and associated with fans, ducts and ventilators, so that the waste vapor laden gases may be drawn through the economizer or vapor condenser in one direction and exhausted to the atmosphere in a cooled condition, and so that fresh air may be drawn through the economizer wherein it is warmed and then directed into the room.

Another object of my invention is to provide suitable ducts for directing warmed air under the roof where it will raise the temperature sufficiently to keep the moisture from condensing.

Another object of my invention is to additionally improve the conditions near the floor of the work room by providing for the installation of an additional exhaust fan which takes the warm air from overhead and discharges it on to the drying rolls or 125

into the drying machinery, thereby preventing any great disturbances of a cooler layer of air near the floor. This cool air will be supplied generally through cracks, crevices and the opening of doors in the room.

Another object of my invention is to pass the heated and vapor laden air through passages in an economizer or vapor condenser arranged to collect the condensed moisture and deliver this moisture to a drip, while the fresh air is drawn through other passages in the economizer or vapor condenser and thoroughly agitated so that it becomes warmed.

Other objects and advantages will become apparent as the apparatus and method are described.

In the drawings, which form a part of this specification,

Figure 1 is a side view showing the air circulating equipment and economizer associated with a paper machine;

Fig. 2 is an end view of the equipment shown in Fig. 1 as taken from the right end of Fig. 1;

Fig. 3 is a plan of the air circulating equipment shown in Fig. 1 with parts omitted;

Fig. 4 is a general elevational view showing the economizer as related to the other units;

Fig. 5 is an end elevation of the economizer or vapor condenser looking in the direction of flow of the hot gases;

Fig. 6 is a side view of the economizer or vapor condenser with the casing removed;

Fig. 7 is an end elevation of part of the economizer or vapor condenser as shown in Fig. 5, but on a larger scale;

Figs. 8 and 9 are end and side elevations, respectively, of the end spacing member which is used to close the ends of the fresh air spaces;

Fig. 10 shows the drain which is used between pairs of plates,

Fig. 11 is an end view of the drain shown in Fig. 10, and

Figs. 12 and 13 represent an end view and plan, respectively, of a modified equipment particularly adapted for use where roof drying is of secondary importance.

Similar reference characters refer to similar parts throughout the several views.

In Figs. 1 to 4, wherein the general layout of the paper drying room is shown, the device will be described in detail, and along with the description of the device the method of operation will be pointed out.

R represents the drying rolls of a paper machine. A hood A is arranged over these drying rolls so that the vapors rising from the rolls will collect under the hood. These vapors are exhausted through the duct B and economizer E by a fan C which exhausts them through a ventilator V to the atmos-

sphere. Another fan G draws air through the fresh air inlet D downwardly through the economizer E through a duct F and past an auxiliary heating coil f. This air is then discharged through the horizontal transverse pipes or ducts H which transmit the air through longitudinal pipes or ducts I arranged overhead and near the roof. A plurality of smaller ducts i are connected with longitudinal ducts I and arranged close up to the roof, as shown in Fig. 2. This warmed air being discharged in the upper regions of the room will keep the upper regions at a comparatively high temperature whereby the air will be able to carry a considerably greater moisture content than it could carry were it cool. Owing to its higher temperature it will remain in the upper regions in the room and will not tend to fall toward the floor.

On one side of the room I sometimes prefer to arrange an exhaust fan J which is provided with an inlet duct L which is overhead and near the roof. It may be as shown in Fig. 2, arranged near the pipes or ducts H. This inlet L will take the warm air from under the roof without disturbing the air near the floor. A steam heater coil K may be arranged in the inlet L to preheat the air before it passes through the fan J. From the fan J the hot air is forced into an underground duct M, and from this duct it is directed through a series of suitably arranged pipes N against the web O on the paper machine.

The heater and fan may in some installations be entirely omitted and in still other installations the fan may be operated without the heater. In such cases the absorbing operation of the fresh air would become the primary function of the operation and the heating and ventilating, the secondary function. The hood over the machine may be present or omitted.

This air at a high temperature which has been directed against the web of the paper machine, will become saturated with vapor and will rise under the hood A, from which it will be drawn by the fan C to the economizer E and discharged to the atmosphere through the ventilator V.

According to the modifications shown in Figs. 12 and 13, the roof drying system, including fan G, duct F, heating coil f, and ducts H, I and i, are replaced by a duct F' which connects directly from the economizer E and the inlet L. This arrangement is particularly desirable where some form of a roof drying device is already installed.

The detailed construction of the economizer or vapor condenser E is shown in Figs. 5 to 11, inclusive. The economizer comprises a number of pairs of corrugated plates 12, 13, of sheet metal, black, processed, galvanized, or coated with protective materials,

- placed parallel and spaced apart forming spaces S, S', through which may be directed the flow of two different currents. Cold air is drawn through the fresh air inlet D, and flows downwardly through spaces S preferably crosswise of the corrugations, whereby it is agitated. The waste hot air from the duct B flows horizontally through the other spaces S' along the corrugations.
- 10 Two pairs of plates 12 and 13 are fastened together at the upper edge, providing a suitable leakproof joint 14. Along the lower edges of each pair of plates 12 and 13 is arranged a longitudinal drain or trough 15 having a sloping lower edge 16 and connection 17 for a drip. This unit of two plates, it will be seen, constitutes substantially a tube having corrugated sides and a drip-receiving trough along the lower edge.
- 15 20 Through the chamber S' thus formed the moisture laden hot gases are drawn by the fan C.

In order to close the ends of the spaces S through which the fresh air is drawn downwardly, sinuous spacing members 19, either made of cast iron or of sheet material, are inserted between the adjacent pairs of corrugated plates, and held in position by rivets, screws, or the like. Any even number of plates may be assembled in pairs along with their spacing members and fastened to a suitable support 20, and this support may be suspended by means of bolt 21 from a channel member 18. Suspension of the plates allows of ease of handling and erection, and provides a flexibility in the device as regards its capacity. A master drain 22 is arranged to receive the moisture which drips from the closing troughs 15 and to conduct the condensed water to a suitable receptacle not shown.

It will be seen that this invention is conducive to the economical operation of a heating and ventilating system on account of saving of the amount of heating surface and steam required to heat the air used for drying, heating and ventilating purposes. This results in a direct saving of fuel.

There is also the recovery of a small amount of fresh warm condensed water which may be used for heating or feed water purposes.

The invention also improves the conditions in the room by maintaining a relatively still or quiet region filled with cool air in which the workers may be comfortable.

Changes in the air conditions, as a result of the circulation above pointed out, are as follows:

Air drawn from outdoors is heated thereby reducing its relative moisture (humidity) to a low percentage.

This air then absorbs vapor under machine room roof thereby becoming slightly

moistened and lowered in temperature and may be directed against the web for drying purposes either immediately or after further reheating as circumstances render desirable.

This air absorbs moisture from the web almost to saturation, the degree of saturation depending upon the volume and temperature of the air directed against the dryers.

This air is then drawn through hood into the economizer where it gives up most of its heat to the fresh air drawn through the economizer from outdoors and cycle of heat is repeated.

The moist air deprived of most of its moisture is exhausted to the atmosphere in a saturated condition at a low temperature.

I claim:

1. In the paper drying art carried on in a building, an economizing process comprising, exhausting heated vapor laden air from above the paper drying machine at substantially atmospheric pressure through passages in a heat exchanger to the atmosphere, drawing through other passages in the heat exchanger atmospheric air, and using it in two stages, first for ventilating the building, and second as an absorbent of vapor leaving the paper drying apparatus.

2. The method of improving air conditions in a building having paper drying apparatus which comprises exhausting the heated vapor laden air at atmospheric pressure produced by the evaporating operation through passages in a vapor condenser to the atmosphere, drawing through other passages in the vapor condenser atmospheric air, and utilizing the warmed fresh air primarily for building ventilation, and secondarily as an absorbent of vapor leaving the evaporating apparatus.

3. In the ventilating of buildings housing paper making machines, the economizing process comprising, exhausting heated vapor laden air from the building space above the drying rolls of a paper making machine, through passages in a vapor condenser to the atmosphere, drawing through other passages in the vapor condenser atmospheric air and discharging the warmed air from the vapor condenser, immediately underneath the roof.

4. In the ventilating art, in connection with paper drying apparatus in a building, an economizing process comprising, exhausting heated vapor laden air through passages in a vapor condenser to the atmosphere, drawing through other passages in the vapor condenser atmospheric air, separating out the condensate and discharging the warmed air from the vapor condenser immediately underneath the roof of said building.

5. In the ventilating art, an economizing process comprising, the exchange by conduc-

70

130

tion of the latent heat of condensation of vapor laden air so as to warm fresh air, warming the upper region of a building with this fresh air, and exhausting this air from the upper region through a heating coil and directing it at the higher temperature against material to be dried.

6. In the ventilating art, an economizing process comprising the utilization by conduction of the latent heat of condensation of vapor in the vapor laden air produced by drying or evaporating apparatus for the purpose of heating and ventilating the building exterior to the drying or evaporating apparatus.

7. In a building having an independent supply of fresh air in the vicinity of the floor and wherein drying apparatus is used, the method of keeping the lower regions thereof cool by leakage through cracks, crevices and open doors, and which comprises exhausting warm air from some overhead point beneath the roof through a duct and discharging it against material to be dried.

8. In the heating and ventilating art, the method of ventilating buildings in one of which drying or evaporating apparatus is used therein, comprising utilization of the escaping mixture of vapor and air at atmospheric pressure to heat an independent current of fresh air for ventilating such buildings outside of the drying apparatus.

9. In the heating and ventilating art, the method of ventilating buildings wherein drying or evaporating apparatus is used, comprising, exhausting the heated vapor laden air at atmospheric pressure through a surface condenser using fresh air as the cooling medium, thus warming the fresh air supply for heating and ventilating such buildings outside of the drying apparatus.

10. The method of supplying warm air to dry the felts on a paper drying machine in a building, which comprises exhausting air from an overhead stratum in said building which has a high temperature owing to paper drying, circulating the air through a heater, and forcing it at higher temperature against the felts of the paper drying machine.

11. In machine buildings of paper mills using steam heated drying cylinders, the process of heating fresh outdoor air for ventilating said buildings external to the drying apparatus from its initial outdoor temperature to a higher temperature, which consists in so directing the flow of fresh air and the flow of waste hot air and vapor resulting from the drying of paper past one another so that heat will be interchanged by conduction from the hot air and vapor to the fresh air.

12. In machine buildings of paper mills using steam heated drying cylinders, the

process of reducing the amount of heat necessary for heating fresh outdoor air required for ventilating said buildings external to the drying apparatus, which consists in raising the temperature of the fresh air from its initial outdoor temperature to a higher temperature by so directing the flow of fresh air and the flow of waste hot air and vapors resulting from the drying operation past one another that heat will be interchanged by conduction from the hot air and vapors to the fresh air.

13. The method of improving air conditions for operators in the machine building of a paper mill in which are operated drying machines, which consists in leaving the lowest stratum of air at the floor at natural conditions, the air required for drying or ventilating said building external to the drying apparatus being taken continuously from the upper part of the building, without disturbing the floor stratum.

14. The method of improving air conditions in paper mill machine buildings in which are operated drying machines, which consists in taking air from the upper part of the building as a supply for hot air required in the drying process or for ventilating said building external to the drying apparatus and admitting cooler outdoor air through openings in walls, so as to produce a cooler stratum of air at the working level near floor.

15. The combination with a hood adapted to receive the vapor-laden air above a paper drying machine in a building, of means for exhausting the vapor-laden air from the hood, a heat interchanger for abstracting both latent and sensible heat of the vapor laden air, and apparatus for supplying fresh air to absorb the heat energy so abstracted and utilizing the fresh air first for ventilating the building external to the drying apparatus and then as an absorbent of moisture leaving the drying machine.

16. The combination with a hood adapted to receive the vapor-laden air above a paper drying machine in a building, of means for exhausting the vapor-laden air from the hood, a heat interchanger for abstracting both latent and sensible heat of the vapor-laden air, apparatus for supplying fresh air to absorb the heat energy so abstracted and using the same for ventilating said buildings outside of hoods, and means for further heating the fresh air.

17. The combination with a hood adapted to receive the vapor-laden air above a paper drying machine in a building, of means for exhausting the vapor-laden air from the hood, a heat interchanger for abstracting both latent and sensible heat of the vapor-laden air and absorbing the heat energy so abstracted, said heat interchanger warming fresh air, and means for distributing the

fresh warm air where it will absorb free heated air onto the paper drying apparatus to absorb moisture.

18. The method of controlling air conditions in a building having paper drying apparatus, which comprises maintaining a stratum of hot dry air immediately beneath the roof and another stratum of relatively dry and cool air adjacent to the floor of the building, exhausting air from a plane intermediate of the areas influenced by the condition of the aforesaid upper and lower air strata through a heater and directing the

19. The method of controlling air conditions in a building having paper drying apparatus, which comprises maintaining a stratum of relatively dry and cool air on the floor, exhausting air from a higher stratum in the building through a heater, and directing the heated air onto the paper drying apparatus to absorb moisture.

EMIL A. BRINER.
